UNITED STATES PATENT OFFICE.

THOMAS JOHNS, OF PHILADELPHIA, PENNSYLVANIA.

HEEL.

1,119,513.

Specification of Letters Patent. Patented Dec. 1, 1914.

Application filed October 26, 1912. Serial No. 728,005.

To all whom it may concern:

Be it known that I, THOMAS JOHNS, a citizen of the United States, residing at Philadelphia, county of Philadelphia, and State of Pennsylvania, have invented new and useful Improvements in Heels, of which the following is a specification.

My invention relates to new and useful improvements in heels for boots or shoes and has for its object to provide an exceedingly simple and effective cushion or rubber heel or heel lift which is so constructed that the means such as nails for fastening the heel to the ordinary shoe heel will not pass directly through the rubber, which often causes the rubber to cut or break thereby making the same impractical and unsightly.

Considerable difficulty is usually experienced when permanently attaching rubber lifts to boots and shoes inasmuch as the fastenings used for attaching the lift soon cut or grind the rubber body away and the lift quickly becomes loose and easily torn off, also when holding washers or bushings are used and embedded directly in the body of the rubber, the same frequently pulls through the rubber after it has been worn and allows the lift to drop off while the fastening means remain in the heel of the shoe. Then again these washers or bushings make the lift heavier than desired, besides making a metallic sound when they come in contact with the pavement after the lift has been worn down. The present invention provides simple means for obviating these difficulties and objections and produces a cushion heel or heel lift having a wearing surface of two different substances which prevents slipping.

As is well known certain conditions of the different pavements often caused by the different forms of weather will allow either a rubber heel or a leather heel to slip, but by combining the two materials, if the pavement is such that the rubber portion of the heel will slip, the leather portion will prevent slipping and vice-versa.

With these ends in view this invention consists in the details of construction and combination of elements hereinafter set forth and then specifically designated by the claims.

In order that those skilled in the art to which this invention appertains may understand how to make and use the same, I will describe its construction in detail, referring

by numeral to the accompanying drawing forming a part of this specification, in which—

Figure 1, is a perspective view of the heel portion of a shoe equipped with a rubber or cushion heel or heel lift made in accordance with my improvement. Fig. 2, a face view thereof, and Fig. 3, a section at the line —— of Fig. 2.

In carrying out my invention as here embodied, 2 represents a shoe equipped with the ordinary leather heel 3 to which is attached my improved rubber or cushion heel or heel lift 4, comprising a body portion 5 of rubber or other suitable elastic material such as a composition of rubber and canvas or the like. Said body portion is formed in the shape of the ordinary shoe heel and may be made in different sizes to correspond approximately with the different sized heels for men's and women's shoes and said body portion has a cavity or cut away portion 6 extending from the outer face in proximity to that end which lies adjacent the shank 80 of the shoe and running from one side to the other. In this cavity or cut away portion is mounted the leather insert 7, preferably having indents 8 to indicate the point where the attaching means 9 such as nails 85 or screws are to be placed.

The inner edge of the leather insert is preferably produced at an angle as indicated by 10 thereby leaving a greater portion of the rubber body along the outer edge 11 of 90 the heel which is generally that portion which comes in contact with the surface on which a person is walking. I do not wish to limit myself to this special cut or shape of leather insert since some persons, especially cripples, often walk more on the inner edge of the heel than they do on the outer edge thereof.

In practice, the rubber or cushion heel or heel lift is cemented to the ordinary boot 100 or shoe heel and this is all that is used for retaining the rear portion of the cushion heel to the shoe heel, but the front portion thereof which must stand the strain incidental to walking, is fastened in place by 105 suitable attaching means such as nails or their equivalent which passes through the leather insert and the thinnest portion of the rubber body. The leather insert forms a good backing material and will prevent the 110 fastening means pulling therethrough and also retain said fastening means in their

same relative positions thereby preventing them from cutting or tearing the rubber.

It has been found in use that the cushion heel or heel lift when formed entirely of rubber and used on women's shoes often tears their clothing because of the friction produced by the rubber between it and the clothing, whereas leather which does not produce such a great amount of friction will 10 permit the clothing to readily slip therefrom and prevent tearing or ripping.

It will be noted that when the cushion heel or heel lift is in place upon the shoe, the front end of the rubber portion is 15 tightly clamped between two pieces of leather, that is, the ordinary leather heel and the insert 7 and when mounted in this manner, the rubber and leather insert may be cut to correspond with the ordinary shoe 20 heel without mutilating the rubber.

Of course I do not wish to be limited to the exact details of construction as here shown as these may be varied within the limits of the appended claims without de- 25 parting from the spirit of my invention.

Having thus fully described my invention, what I claim as new and useful, is—

1. As an article of manufacture a cush-

ioned heel for shoes comprising a resilient body arranged to entirely cover the face of the shoe heel, said body having a cut-away portion or cavity at its forward end, the end wall of said cavity extending obliquely from the outer edge of the body adjacent its forward end to the inner edge thereof 35 adjacent its rear end, and a leather insert of the same shape and size of the cavity mounted in said cavity to complete the tread surface of the heel and expose the resilient body only at the rear outer portion of the 40 heel.

2. As a new article of manufacture a cushioned heel for a shoe comprising a resilient body having a cut-away portion to leave a raised tread portion with an oblique front 45 wall and a leather insert of the same shape and size as the cut-away portion adapted to complete the heel tread as shown and described.

In testimony whereof, I have hereunto af- 50 fixed my signature in the presence of two subscribing witnesses.

THOMAS JOHNS.
